UNITED STATES PATENT OFFICE.

GUSTAV HANKE, OF ADAIR, IOWA, ASSIGNOR OF ONE-HALF TO ED. T. WAHLERT, OF SAME PLACE.

TRACE-BUCKLE.

SPECIFICATION forming part of Letters Patent No. 639,033, dated December 12, 1899.

Application filed June 16, 1898. Serial No. 683,580. (No model.)

To all whom it may concern:

Be it known that I, GUSTAV HANKE, a citizen of the United States, residing at Adair, in the county of Adair and State of Iowa, have 5 invented a new and useful Trace-Buckle, of which the following is a specification.

This invention relates to buckles designed more especially for use in connection with traces and heavy harness-straps, and has for 10 its object to enable the trace or strap connected therewith to be quickly lengthened and shortened with the greatest ease possible.

For a full understanding of the merits and advantages of the invention reference is to 15 be had to the accompanying drawings and the following description.

The improvement is susceptible of various changes in the form, proportion, and the minor details of construction without departing 20 from the principle or sacrificing any of the advantages thereof, and to a full disclosure of the invention an adaptation thereof is shown in the accompanying drawings, in which—

25 Figure 1 is a perspective view of a trace-buckle, showing the application of the invention. Fig. 2 is a plan view of the buckle, the billet-loop being omitted. Fig. 3 is a detail section on the line X X of Fig. 2 looking in 30 the direction of the arrow, the dotted lines showing the position of the tongue when disengaging a trace or strap therefrom. Fig. 4 is an end view.

Corresponding and like parts are referred 35 to in the following description and indicated in the views of the drawings by the same reference characters.

The buckle-frame comprises side loops 1 for attachment therewith of the back and 40 belly-band straps, an end loop 2 for the breeching, a cross-bar 3 to receive the hame-tug, and an end cross-bar 4. A recess 5 is formed in one side of the end bar 4 at its outer edge and is centrally notched, as shown at 6. The 45 tongue 7 has its butt-end entering the notch 6 and normally rests against the inner wall of the recess 5, whereby said tongue is normally held at right angles to the plane of the buckle-frame.

50 In accordance with the spirit of this invention the tongue 7 is adapted to turn so as to

permit the trace or harness-strap to be readily disconnected therefrom. Hence it has pivotal connection with the buckle-frame within the recess 5. Journals 8 project laterally 55 from opposite sides of the tongue and are the means whereby the tongue is pivotally mounted, keepers 9 embracing the journals 8 and connecting them with the buckle-frame in such a manner as to admit of the tongue turning freely. The journals may form end portions of a pin passing through an opening formed in the butt-end of the tongue, and, if desired, the tongue may turn upon the pin, in which instance the pin may be secured to the 60 buckle-frame in any desired manner. A spring 10, coiled intermediate of its ends, is mounted upon a journal of the tongue and has its end portions connected, respectively, with the tongue and buckle-frame and serves 65 to hold the tongue against the inner wall of the recess 5 and at right angles to the frame of the buckle-frame, so as to prevent accidental disengagement of the trace or harness-strap from the tongue. The billet-loop 11 co- 70 operates with the buckle-frame and tongue to maintain the trace or harness-strap in engagement with the tongue after the parts have been properly assembled and positioned. When it is required to lengthen or shorten 75 the trace or strap, a backward pull thereon will cause the tongue to turn upon its pivotal support and easily withdraw from the opening of the trace or strap in which it is fitted.

Having thus described the invention, what 80 is claimed as new, and desired to be secured by Letters Patent, is—

1. In a trace-buckle, the combination with a buckle-frame having a bar recessed in one side, of a swinging tongue supported within 85 said recess and fitting normally against one of the walls of said recess, a spring acting against the tongue and serving to hold the same in contact with said wall, and a sliding trace-receiving bail or loop for the attachment of a hame-strap, substantially as described.

2. In a trace-buckle, the combination with a buckle-frame having an end bar recessed in one side, and having a transverse notch extending into the recess, of a tongue having its 90 butt-end fitted into the notch and pivotally 95

secured in said recess and bearing against the inner wall thereof, a spring exerting its pressure upon the tongue to hold the latter in contact with said wall and a sliding trace-receiving loop, substantially as described.

3. In a trace-buckle, the combination with a buckle-frame having an end bar recessed longitudinally thereof in one side and having a notch extending into the recess between the ends thereof, of a tongue the butt portion of which is disposed in said notch, journals extending oppositely from the tongue, keepers for securing the journals within the recess of the buckle-frame, a spring mounted upon one

of the journals and bearing against the tongue 15 and buckle-frame respectively and serving to hold said tongue in its normal position against one of the walls of the recess, and a sliding trace-receiving loop for the attachment of a hame-strap, substantially as de- 20 scribed.

In testimony that I claim the foregoing as my own I have hereto affixed my signature in the presence of two witnesses.

GUSTAV HANKE.
